Primary Examiner — Anhdao Doan(74) *Attorney, Agent, or Firm* — Knobbe Martens Olson & Bear LLP(57) **CLAIM**

The ornamental design for a microfluidic cartridge, as shown and described.

DESCRIPTION

FIG. 1 is a top, left, and front perspective view of an embodiment of a microfluidic cartridge, showing our new design;

FIG. 2 is an exploded view thereof;

FIG. 3 is a top plan view thereof;

FIG. 4 is a bottom plan view thereof;

FIG. 5 is a left side plan view thereof;

FIG. 6 is a right side plan view thereof;

FIG. 7 is a front plan view thereof; and,

FIG. 8 is a back plan view thereof.

The broken lines depict portions of the microfluidic cartridge that form no part of the claimed design.

1 Claim, 5 Drawing Sheets(56)
